US00D988717S

(12) United States Design Patent (10) Patent No.: US D988,717 S
(45) Date of Patent: * Jun. 13, 2023

(54) PASSPORT HOLDER

(71) Applicant: WENZHOU POMPEI LEATHER GOODS CO., LTD, Wenzhou (CN)

(72) Inventor: Aizhen Liao, Wenzhou (CN)

(*) Notice: Patent file contains an affidavit/declaration under 37 CFR 1.130(b).

() Term: 15 Years

(21) Appl. No.: 29/809,557

(22) Filed: Sep. 29, 2021

(51) LOC (14) Cl. 03-01

(52) U.S. Cl.

USPC D3/249

(58) Field of Classification Search

USPC D3/247-253, 301, 303

CPC A45C 11/00; A45C 2011/002; A45C 1/06;

A45C 11/182; A45C 11/18

See application file for complete search history.

Assistant Examiner — Samantha Lynne Brodowski

(57) CLAIM

The ornamental design for a passport holder, as shown and described.

DESCRIPTION

FIG. 1 is a perspective view of a passport holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

FIG. 12 is an enlarged view of portion 12 shown in FIG. 2;

FIG. 13 is an enlarged view of portion 13 shown in FIG. 2; and,

FIG. 14 is a perspective view of the passport holder where the passport holder is in a configuration of use.

The dash-dash broken lines in the drawings depict portions of the passport holder that form no part of the claimed design. The dot-dash broken lines represent boundaries of the enlarged portions and form no part of the claimed design.

1 Claim, 14 Drawing Sheets
